To all whom it may concern:

Be it known that I, Peter Muller-Munk, a citizen of the United States, residing at Pittsburgh, in the county of Allegheny and State of Pennsylvania, have invented a new, original, and ornamental Design for Clocks, of which the following is a specification, reference being had to the accompanying drawing forming part thereof, in which:

The figure is a perspective view of a clock showing my new design. The back and end of which

The numerals shown through the arcuate opening on the face of the clock are merely representative.

I claim:

The ornamental design for a clock, substantially as shown and described.

PETER MULLER-MUNK.
